CIRCUIT INTERRUPTER

Howard W. Graybill, Pittsburgh, Pa., assignor to
Westinghouse Electric Corporation, East Pitts-
burgh, Pa., a corporation of Pennsylvania

Application September 14, 1944, Serial No. 553,990

21 Claims. (Cl. 200—149)

1

This invention relates, generally, to electric circuit interrupters and, more especially, to such interrupters which employ a material along the arc path which evolves an arc-extinguishing gas when in proximity to an electric arc, for the purpose of extinguishing the arc.

In circuit interrupters, such as switches designed to open load currents, where repeated operations are required without renewal of any parts of the interrupter, interruption by the use of a blast of arc-extinguishing gas through the arc, which gas is obtained from a solid gas-evolving material activated by the arc, have been found to be objectionable because of the relatively short life of the gas-evolving material. The action of the arc on such gas-evolving materials results in erosion of the material, and while this erosion or wear is small at first, being on the order of .001 inch per interruption, it is of importance because these interrupters depend in part for rapid and efficient arc extinction on the high arc voltage obtained by mechanically restricting the arc in a narrow passage which is formed at least in part by the aforesaid gas-evolving material. These narrow arc passages are generally made as narrow as practicable to obtain maximum arc voltage, and consequently, erosion of the gas-evolving material results in widening of the arc passage and consequent lowering of arc voltage and resultant loss in efficiency and speed of interruption. Moreover the erosion becomes progressively worse, because widening of the slot results in a longer arcing time and consequently a greater amount of erosion.

One object of this invention is to provide in circuit interrupters of the self-generated gas blast type, novel means for reducing erosion of any one point of the gas-evolving material so as to materially prolong the effective life of such material.

It has been found that in interrupters of the self-generated gas blast type, most of the erosion of the gas-evolving material occurs at a relatively small area where initial separation of the interrupter contacts occurs.

Accordingly, another object of this invention is to provide novel means in an interrupter of the type described, for distributing the major portion of the erosion occurring on successive interruptions over different parts of the gas-evolving material.

A more specific object of this invention is to provide in an interrupter of the self-generated gas blast type, novel means providing for rela-

2

tive movement of the contacts and gas-evolving material in response to successive interrupting operations, so that different parts of such material are exposed to the maximum eroding effect of the arc on successive interruptions.

These and other objects of this invention will become more apparent upon consideration of the following detailed description of a preferred embodiment thereof, when taken in connection with the attached drawings, in which:

Fig. 1 is a partial side elevation view of a switch constructed in accordance with this invention;

Fig. 2 is an end view of the switch shown in Fig. 1, with the arc chute shown in a section taken substantially along the line II—II of Fig. 3;

Fig. 3 is a longitudinal section taken through the arc chute shown in Fig. 1, with the section being taken substantially on the line III—III of Fig. 2;

Fig. 4 is a view similar to Fig. 3, but illustrating the positions of the parts when the switch blade is in its closed circuit position;

Fig. 5 is a longitudinal section view, partially in elevation, illustrating a modified form of this invention;

Fig. 6 is a longitudinal section view of the interrupting device shown in Fig. 5, taken substantially on the line VI—VI thereof;

Fig. 7 is a longitudinal view of still another form of circuit interrupter embodying this invention, with certain of the parts shown in elevation;

Fig. 8 is a transverse section of reduced size, taken through the interrupter shown in Fig. 7, substantially on the line VIII—VIII thereof; and

Fig. 9 is a partial longitudinal section view of still another type of interrupter embodying this invention.

40 This invention is illustrated on Figs. 1 to 4 of the drawings as being embodied in a load break disconnect switch of the general type illustrated in H. L. Rawlins Patent No. 2,308,026, issued January 12, 1943, to the same assignee as this invention.

45 Although this invention has certain particular cooperation with a switch of the type disclosed in the aforesaid Rawlins patent, it is to be understood that the invention also may be used with other types of circuit interrupters wherein it may also find certain novel features of cooperation.

46 In general, the particular switch illustrated in Figs. 1 to 4, comprises a pair of supporting insulators 2 and 4, such as porcelain insulators or the like, on which the switch proper is mounted.

The supporting insulator 2 is illustrated as having a hinge tongue casting 6 secured thereon as by bolts 7, and it is provided with an integral terminal pad 8 to which a line conductor may be secured in any desired manner. Hinge tongue 6 is apertured for the reception of a pivot bolt 10 for pivotally mounting a split switch blade 12. Preferably pivot bolt 10 is provided at each side of switch blade 12 with spring washers 11, for the purpose of providing a predetermined contact pressure between the sides of the split blade 12 and hinge tongue 6.

Supporting insulator 4 is adapted to support a break contact tongue 14 having an integral base which is secured to insulator 4, as by bolts 15, and having an integral outwardly extending terminal pad 17, to which a line conductor may be secured in any desired manner. The outer end of switch blade 12 has the sides thereof secured together by a bolt 19 having spring washers 21 thereon at the outer sides of the blade, and break contact tongue 14 is preferably provided with a slot (not shown) for receiving bolt 19 in the closed position of the switch illustrated in Fig. 1. An actuating handle 16 is adapted to be secured between the outer ends of the sides of blade 12, and is preferably provided with a hook eye 18 for the reception of a hook stick operating member or the like.

It is believed apparent that the structure thus far described is that of a conventional disconnect switch having a blade 12 pivotally mounted at one end for movement of the other end into and out of engagement with break contact tongue 14, to close the circuit when in engagement, and to provide a safe air gap in the circuit when out of engagement.

For the purpose of interrupting load currents, switch blade 12 is provided with an auxiliary snap-acting blade 20 adapted to be mounted on one side of blade 12. The mounting for auxiliary blade 20 comprises a mounting fixture 22 having spaced plates, one of which is adapted to lie against the inner end of auxiliary blade 20 and be secured thereto as by screws 24. The other plate 25 of mounting fixture 22 is adapted to lie against the adjacent side of split blade 12. The auxiliary blade 20 and mounting fixture 22 are apertured for the reception of a pivot bolt 26 so as to be freely rotatable on this bolt, which is secured in main blade 12. Mounting fixture 22 has the plates 25 thereof maintained in spaced apart relation by integral transversely extending connecting bars 28 and 30. The plate 25 of mounting fixture 22 which lies adjacent main blade 12 is notched, as shown, at 32 to receive a stop screw 34 mounted in main blade 12. The purpose of stop screw 34 is to limit pivotal movement of auxiliary blade 20 relative to main blade 12. A spring 36 is coiled about pivot bolt 26 and reacts between one screw 24 and stop screw 34 to normally bias auxiliary blade 20 in a counterclockwise direction about pivot bolt 26 to maintain stop screw 34 in engagement with the side of notch 28, wherein the auxiliary blade lies substantially parallel to main blade 12, so as to be received in an arc chute 37 positioned at one side of break contact tongue 14.

The structure thus far described is substantially identical with that disclosed in the aforementioned Rawlins patent, and, accordingly, for a more complete description of the parts and their operation, reference is hereby made to such Rawlins patent. This invention is primarily concerned with the construction of arc chute 37 and

with certain aspects of its cooperation with the switch structure heretofore described. Arc chute 37 comprises a pair of plates 38 which may be machined or molded complementary in shape. Plates 38 may be of any desired insulating material but are preferably of an insulating material which is capable of evolving an arc-extinguishing gas when in proximity to an electric arc, such, for example, as fiber, a synthetic resin, or the like. The plates 38 are each provided with integral flange portions 40 and 42 along adjacent edges thereof, for the purpose of spacing the plates a predetermined distance apart when the plates are assembled with the flanges in abutting relation, and secured together, for example, as by bolts 44. Flanges 42 are interrupted adjacent flange 40 to receive the upright arm 46 of an angled supporting bracket, the base portion 48 of which is adapted to be secured to insulator 4 between the insulator and the base of break contact tongue 14. Each plate 38 is also preferably recessed to receive a contact jaw 50, with one jaw located at each side of upright arm 46 of the supporting bracket, and secured in position by one of bolts 44. Each plate is also provided with a generally circular depressed portion 52 for receiving a circular disk 54 also of insulating material, and particularly of an insulating material which is capable of evolving an arc-extinguishing gas when in proximity to an electric arc, such, for example, as the materials given above for plates 38. Although circular disks 54 are of a gas-evolving insulating material, they need not be of the same material as plates 38, especially if plates 38 are of an inert insulating material.

Disks 54 of gas evolving material are rotatably mounted on plates 38, as by rivets 56, and are provided about their periphery with ratchet teeth 58, adapted to cooperate on the one hand with a spring holding pawl 60 secured to a flange 40 in any desired manner, such, for example, as by screws 61. Ratchet teeth 58 on disks 54 are also adapted to cooperate with a pawl lever 62 pivotally mounted between plates 38 on a pivot pin 64. A spring 66 coiled about pivot pin 64 is provided for biasing pawl lever 62 in a clockwise direction about pivot 64, as viewed in Figs. 1, 3, and 4, so that in the open circuit position of the switch, pawl lever 62 is held against the adjacent portion 72 of flange 40, as shown in Fig. 3. Pawl lever 62 is provided at its outer end with a spring pawl portion 68 adapted to engage ratchet teeth 58, and the inner end of pawl lever 62 is provided with a transversely extending toe 70 positioned in the path of movement of auxiliary switch blade 20, for a purpose to be described. It will be observed that arc chute plates 38 are provided with depressions opening into circular depression 52 for receiving pawl 60, pawl lever 62, and contact jaws 50. Arc chute plates 38 are also provided with an outwardly flared entrance 74, at the point where auxiliary blade 20 enters the chute during a circuit closing operation.

In the operation of the switch, and assuming it is desired to open the circuit by moving the switch from the closed circuit position shown in Figs. 1 and 4, a hook stick or other operating member is inserted in hook eye 18, and main blade 12 is pulled away from break contact tongue 14. However, auxiliary blade 20 is held frictionally between contact jaws 50, while the auxiliary blade rotates on pivot bolt 26 and stresses spring 36. This movement of the parts continues until main switch blade 12 is separated a substantial dis-

tance from break contact tongue 14, and the other side of notch 32 in plate 25 of mounting fixture 22 engages stop screw 34, whereupon continued opening movement of main switch blade 12 causes auxiliary blade 20 to be pulled out of contact jaws 50. As soon as auxiliary blade 20 escapes from frictional engagement with contact jaws 50, its biasing spring 36 acts to rapidly move the auxiliary blade relative to main blade 12 in a pivotal manner about bolt 26 to restore it to the position shown in Fig. 1 where it lies alongside main blade 12. Preferably this snap action of auxiliary blade 20 takes place substantially throughout the narrow slot formed between arc chute plates 38 and disks 54 therein, so that the arc drawn upon separation of auxiliary blade 20 from contact jaws 50 will be very rapidly elongated through the arc chute and extinguished therein. The arc-extinguishing action of the arc chute is due in part to the rapid elongation of the arc by snap movement of auxiliary blade 20, which rapidly increases the arc voltage, and in part to physical confinement of the arc in the narrow space between the arc chute plates and disks 54, and finally by the action of arc-extinguishing gas evolved from the material of disks 54 and plates 38 if the latter be made of gas evolving material, which acts to supply a blast of unionized gas through the arc and out the open sides of arc chute 37, to further increase the resistance of the arc path at current zero by replacing the ionized particles in the arc path by the unionized particles of the evolved gas. These several arc-extinguishing actions jointly produce extremely efficient arc-extinguishing action. The space or slot defined between arc chute plates 38 and disks 54 is made as small as possible, being limited only by the thickness of auxiliary blade 20.

After the circuit has been opened in the manner described above and it is desired to close the switch, main blade 12 is rotated in the opposite or clockwise direction about its pivot bolt 10 by means of hook eye 18, and this carries auxiliary blade 20 along with it into arc chute 37. After main blade 12 and auxiliary blade 20 have engaged their respective contacts, and prior to the attainment of fully closed position, it will be observed that the outer end of auxiliary blade 20 will engage the toe 70 of pawl lever 62 to rotate the pawl lever in a counterclockwise direction about its pivot 64. This causes pawl portion 68 of the pawl lever to engage a ratchet tooth 58 on insulating disks 54 to rotate the disks a distance corresponding to approximately the distance between ratchet teeth in a clockwise direction. Spring holding pawl 60 is provided for the purpose of preventing retrograde movement of disks 54 when the switch is opened, and pawl lever 62 is moved from the position shown in Fig. 3 clockwise to the position shown in Fig. 4 by its biasing spring 66. This permits pawl portion 68 of the pawl lever to engage the next ratchet tooth in a counterclockwise direction when the switch is reclosed. It is thus apparent that each time the switch is closed, disks 54 are rotated a predetermined amount in a clockwise direction. It will be observed that the outer ends of spring holding pawl 60 and pawl portion 68 are bifurcated, to permit auxiliary blade 20 to move between the furcations thereof during its opening and closing movements. Also, pawl lever 62 preferably is apertured to provide a space for coil spring 66, and toe 70 extends substantially transversely with respect to blade 20.

As previously stated, each time the circuit is opened, the action of the arc on the gas evolving material comprising disks 54 and plates 38 has an eroding effect thereon, so that the width of the slot in which the arc is drawn is very slightly increased by each circuit interrupting operation. Such erosion, of course, varies with the value of current interrupted and with the length of time the arc is maintained. Tests have shown that such erosion is very much greater at a point closely adjacent the point of initial contact separation than elsewhere, so much so that erosion at a point an inch or more away from the stationary contact jaws 50 is negligible by comparison. Furthermore, in an arc chute having stationary walls, it is possible to interrupt a given value of current at a given voltage at the end of the first half cycle when the arc chute is new. However, after about 100 operations at the same current and voltage, the chute will show erosion from one-eighth to one-fourth of an inch over an area about one-half of an inch in diameter closely adjacent the stationary contacts. Moreover, after this number of operations, the arc during interruption will continue for as many as four to six half cycles, with a resulting erosion from five to ten times that occurring when the chute is new. This becomes progressively worse as the number of operations is increased, and eventually reaches a point where the arc is not extinguished within the chute, but is drawn outside the chute, resulting in a flashover and failure. With an arc chute constructed in accordance with this invention wherein disks 54 are in proximity to stationary contact jaws 50, and where these disks are moved so as to present different surfaces to successive arcs, it is obvious that the erosion of a great number of successive arcs is distributed over a relatively wide area of disks 54, so that the width of the arc passage is increased but a small amount, if any, even after a relatively large number of successive circuit interrupting operations have occurred. With a structure such as that disclosed herein wherein different surfaces of gas evolving material are exposed in proximity to successive arcs, it is apparent that the efficient life of such an arc chute will be multiplied a number of times substantially equal to the number of ratchet teeth on disks 54. In other words, when a chute constructed in accordance with this invention is new, it will operate with the same characteristics as the first operation of a new chute having fixed walls, for the number of operations required before disks 54 are rotated one complete revolution. It is only after this number of successive operations has occurred, that any eroded surface at all is positioned in proximity to the arc, and because the arcing time on these first operations has been very short, the erosion is correspondingly very low. Each complete revolution of disk 54 thus results in an amount of erosion of the gas evolving material at any one point, substantially equal to the resulting from a single operation of a chute having fixed walls. This invention, therefore, results in multiplying the life of the chute by approximately the number of operations required to rotate disks 54 one complete revolution.

In the embodiment of the invention shown in Figs. 5 and 6, there is illustrated a circuit interrupter comprising a tubular housing 76 of any desired insulating material, such for example, as a molded insulating material or the like. A cap structure 78 is threaded on the lower end of tubular housing 76, and the cap structure is

apertured for the reception of a terminal bolt 80 having a shoulder 82 adapted to be drawn against the inner side of cap structure 78 by a nut 84. Preferably integral with terminal bolt 80 there is provided a supporting post 86 extending up into housing 76, for the purpose of rotatably supporting thereon a filler plug 88. The filler plug is positioned centrally of the housing and extends longitudinally thereof for the purpose of forming the inner wall of an annular arc chamber. In order to assist in extinguishing arcs formed in proximity to the outer surface of filler plug 88, it is preferably composed of an insulating material which is capable of evolving an arc extinguishing gas when in proximity with an electric arc, such for example, as fiber, a synthetic resin, or the like. Filler plug 88 is provided with a longitudinally extending recess 90 therein for receiving supporting post 86, and bearings 92 are provided between the post and filler plug to rotatably mount the plug on the post. As shown, bearings 92 are of the ball type, so that the plug will be freely rotatably mounted on the post. A tubular member 94, also of a gas-evolving insulating material like plug 88, is rotatably mounted in housing 76 by ball bearings 93 or the like, located adjacent opposite ends thereof, and held in place against a shoulder provided adjacent the lower end of housing 76 by a threaded collar 96 threadedly engaged in the upper end of housing 76.

Spaced contact arms 100 are provided integral with terminal bolt 80, to provide spaced contact jaws located at one point at the lower end of the annular space between tubular member 94 and plug 88, for receiving therebetween the lower end of a contact rod 102 in the closed circuit position of the interrupter. Contact rod 102 is illustrated as mounted on the transverse head 105 of a contact actuating rod 104. Any suitable means may be provided for longitudinally moving contact actuating rod 104 to move the lower end of contact rod 102 into and out of engagement between contact jaws 100.

The structure thus far described operates in a known manner to interrupt the circuit and extinguish any arc drawn during a circuit interrupting operation, by confining such arcs in the narrow annular space between tubular member 94 and plug 88, while subjecting the arc to a blast of the gases evolved from the material of plug 88 and tubular member 94. The arc-extinguishing action thus comprises a physical restriction of the arc core to create a high arc voltage, acting in conjunction with a gas-blast which acts to replace ionized particles in the arc path with unionized particles, so as to prevent restriking of the arc at a current zero.

In order to prevent undue wear or erosion of plug 88 or tubular member 94, these members are mounted for rotation substantially about their longitudinal axis, as explained above, and means are provided for rotating these members, so that successive arcs are not struck in proximity with the same portions of these members. For producing rotation of plug 88 and tubular member 94, the upper end of plug 88 is provided with a series of annularly arranged notches 106, and the upper end of the tubular member is provided with an annular series of notches 108. Spring 70 actuating pawls 110 and 112 are provided on the underside of head 105 of contact actuating rod 104, for engagement with notches 108 and 106, respectively, when the actuating rod is moved to close the circuit. In a similar manner, the

lower ends of plug 88 and tubular member 94 are each provided with an annular series of notches 116 and 114, respectively, for cooperation with spring retaining pawls 120 and 118, respectively. The pawls are mounted in any desired manner on their respective supports, for example, as by screws 111.

The interrupter is shown in Fig. 5 in its open circuit position, and it will be observed that, when 10 actuating rod 104 is moved downwardly to close the circuit, spring pawls 110 and 112 will engage with the respective notches 108 and 106, so that continued downward movement bends the pawls to cause rotation of plug 88 and tubular member 94 about their longitudinal axis. Retainer pawls 118 and 120 are arranged to slip over their respective notches 114 and 116 to permit such rotation of the plug and tubular member when the switch is closed, but prevent rotation of these parts in the opposite direction. Accordingly, when the interrupter is opened by moving the actuating rod upwardly, pawls 118 and 120 will retain plug 88 and tubular member 94 at the positions to which they were advanced by pawls 110 and 112 on the preceding circuit closing operation. As shown in Fig. 6, pawls 110 and 112 are of the same extent, and accordingly will be flexed and rotate the plug and tubular member the same linear amount during closing of the interrupter. However, since notches 108 and 106 are at different radii from the longitudinal axis of the interrupter, they will be caused to rotate different angular amounts on each circuit closing operation, so that the portions thereof which 20 were exposed to the arc on the preceding circuit interrupting operation will be displaced from each other as well as being advanced to a position away from proximity with the arc. It can thus be seen, that the interrupter shown in Figs. 25 5 and 6 is not only capable of presenting fresh surfaces of gas-evolving material to successive arcs, but additionally moves the inner and outer walls of the arc passage different angular amounts, to prevent any portions of these walls 30 which are subjected to one arc from becoming lined up opposite each other so as to both be again subjected to an arc at the same time, on some future circuit interrupting operation. Moreover, it will be noted that pawls 110 and 112 are 35 inclined in opposite directions, so that upon closing the interrupter, plug 88 and tubular member 94 will be rotated by these pawls in opposite directions, to thus further increase displacement of any two portions of plug 88 and tubular member 94 which have been subjected to one arc, and therefore further lessen the chances that these 40 same two portions might become lined up opposite each other again, to be subjected to some future arc at the same time.

In Figs. 7 and 8 of the drawings, there is illustrated still another type of circuit interrupter and the manner in which this invention may be applied thereto. This interrupter is illustrated as being mounted in a tubular casing 122 of insulating material, such for example, as a molded insulating material, or the like. The lower end of casing 122 is threaded for the reception of a threaded closure plug 124 also of insulating material, similar to that of casing 122. Closure plug 124 is adapted to support the connecting portion of a generally U-shaped contact structure 126 having projecting contact portions 128 mounted on the inner side of the legs thereof adjacent their opposite ends. Preferably contact portions 128 are of a different material from

contact structure 126, and should be of some arc resistant material, such for example, as a tungsten alloy. Contact structure 126 is centrally apertured so as to receive and be secured on the end of a terminal bolt 130. Bolt 130 is secured to the contact structure in any desired manner, such for example, as by welding or the like, and itself is secured in an aperture provided in closure plug 124 by a nut 132 threaded on the outer end thereof.

A tubular member 136 of insulating material, preferably of a gas-evolving insulating material such as the material forming the arc passages in the previously described embodiments of this invention, is rotatably mounted within casing 122 by bearings 134, preferably of the antifriction ball type. A securing collar 138 is threadedly engaged with the inner wall of casing 122 to hold tubular member 136 in engagement with a shoulder on the inner wall of casing 122 located adjacent contact portions 128. Contact actuating rod 140 extends into casing 122, and is provided at its inner end with an enlarged contact head 142 of a size to engage between contact portions 128. Contact head 142 is provided with a central recess which is threaded for engagement with a threaded supporting rod 144 for the purpose of supporting a contact follower 148. Follower 148 is also of insulating material, preferably an insulating material which is capable of evolving a gas to extinguish the arc, like tubular member 136, and it is provided with a longitudinally extending bore 150 for receiving supporting rod 144, and is rotatably mounted thereon by bearings 146, and held in place by a retaining collar 152 threadedly mounted in the upper end of bore 150.

The lower end of follower 148 is provided with an annular series of notches 154 adapted to engage spring actuating pawls 156 mounted on contact structure 126, for example, as by screws 172. The upper end of follower 148 is also provided with an annular series of notches 158 for cooperation with spring retaining pawls 160 mounted on the underside of contact head 142. Tubular member 136 is provided substantially centrally around the outside thereof with a series of notches 162 for engagement with a spring retaining pawl 164 secured on the inner wall of casing 122. The upper end of tubular member 136 is also provided with an annular series of notches 166 adapted to be engaged by spring actuating pawls 168 secured on transversely oppositely extending arms 170 mounted on actuating rod 140.

The operation of the interrupter shown in Figs. 7 and 8 is quite similar to that shown in Figs. 5 and 6. The interrupter is illustrated in Fig. 7 in the open circuit position, so that when actuating rod 140 is moved downwardly to close the circuit, it will be observed that actuating pawls 168 will engage notches 166 to rotate member 136 a predetermined increment about its longitudinal axis, and at the same time, notches 154 on follower 148 will engage actuating pawls 156 to cause rotation of the follower substantially the same linear amount about its longitudinal axis. When the interrupter is moved back upwardly, to move contact head 142 out of engagement with contact portions 128, it will be observed that the arc will be drawn upwardly within the tubular member 136, and because follower 148 moves with contact head 142, it follows the arc into tubular member 136 and restricts the arc in the narrow annular space between the follower and the inner surface of tu-

bular member 136. The arc is thus extinguished in substantially the same manner as in the embodiment of the invention shown in Figs. 5 and 6, the only substantial difference being that the annular arcing space, in this embodiment of the invention, may be much narrower because it is not limited by the size of the conductor necessary to carry the current as is the interrupter shown in Figs. 5 and 6, where it is necessary that the current-carrying member move through the arc space. Here, as in the embodiment of the invention shown in Figs. 5 and 6, follower 148 and tubular member 136 may be rotated each time by their respective actuating pawls in the same 15 rotative direction, but are preferably rotated in opposite directions as shown on the drawings. It will also be observed that retainer pawls 160 and 164 will act to retain follower 148 and tubular member 136 at the position to which they are advanced by the actuating pawls, so that the arcs of successive circuit interrupting operations are exposed to different surfaces of follower 148 and tubular member 136.

The particular interrupter illustrated in Fig. 9 of the drawings is similar in most respects to that disclosed in the patent to J. M. Wallace and H. L. Rawlins 2,286,131, issued June 9, 1942, to the same assignee of this invention. This interrupter, in general, is supported between a metallic end cap structure 174 and a supporting ring 176 spaced therefrom, and held in spaced fixed relation by threaded engagement with the opposite ends of a tube 178 of insulating material, such as a molded insulating material or the like. For 25 added insulating qualities, an outer weatherproof tube of insulating material 180 may also be held between cap 174 and ring 176 in engagement with packing material 182 positioned at opposite ends thereof. Such an outer tube 180 is preferably 30 of an impervious insulating material, such for example, as porcelain or the like. Tube 178 is provided with a tubular liner 184 which is of an insulating material capable of evolving an arc-extinguishing gas, similar to the materials of the 35 previously described embodiments of the invention which form walls of an arc space. Substantially centrally of this structure, there is provided a conductor rod 186 having a tubular cover 188 thereon which is spaced from tubular lining 40 184, to form an annular arc space 192 therebetween. Cover 188 is also preferably of a gas-evolving insulating material similar to liner 184. Preferably the outer end of arcing space 192 adjacent cap 174 is filled by an annular plug 190 45 also of insulating material, which is threadedly 50 engaged with liner 184 and cover 188.

The contact structure and actuating mechanism are supported within a metal casing 193 secured to supporting ring 176, as by bolts 191, 55 only one of which is shown. Supporting plates 194 are secured to supporting ring 176 within casing 193, for the purpose of supporting therebetween a pair of opposed contact arms 196 on pivot pins 198, which are located at opposite sides of the arcing space 192. The outer ends of contact arms 196 are directed toward each other, for engagement in opposite sides of a groove provided in a contact ring 200 mounted on the inner end of conductor rod 186, and held in place by a tapered nut 202. Contact arms 196 are biased to engage contact ring 200 by compression springs 206 mounted on toggle levers 204, which are pivoted to the inner ends of the contact arms, and slotted at their other ends for sliding on support 60 pins 208.

Supporting plates 194 (only one of which is shown) each has an arcuate extension 212 extending toward the opposite wall of casing 193, for the purpose of slidably supporting therebetween an arc-extinguishing tube 210. Extensions 212 of the supporting plates are preferably connected at spaced points by rings 214, 216 and 217. The supporting plate extensions 212 are each provided with a guide slot 218 for a purpose to be described. Arc-extinguishing tube 210 is provided at its outer end with an actuating member 226 having an extension threadedly mounted in the adjacent end of the tube to be secured thereto, and this member is rotatably mounted in a bearing sleeve 228 located between the head of actuating member 226 and the adjacent end of arc-extinguishing tube 210, by ball bearings 230, or the like. Bearing sleeve 228 is provided with actuating pins 220 at opposite sides thereof to be received in guide slots 218 to prevent rotation of the bearing sleeve about its longitudinal axis, and these pins 220 also extend into notches 222 provided in the outer ends of actuating levers 224 (only one shown).

In operation, the contact arms 196 are separated from contact ring 200, and the resulting arc is elongated in the annular arc space 192 in response to movement of actuating lever 224 to the left. Actuating lever 224 may be actuated in any desired manner, preferably in the manner illustrated in the aforementioned Wallace and Rawlins patent, which also contains a more complete description of the various parts of the interrupter and their mode of operation. Accordingly, for a better understanding thereof, reference is hereby made to the aforesaid Wallace and Rawlins patent.

In accordance with this invention, arc-extinguishing tube 210 is rotatably mounted substantially about its longitudinal axis, as described above, and means are provided for rotating this tube a predetermined increment between successive circuit interrupting operations. This rotating means comprises the provision of an annular series of notches 232 provided on the outer end of actuating member 226, for engagement with a spring actuating pawl 234 secured to the adjacent wall of casing 193, so as to engage the pawl whenever arc-extinguishing tube 210 reaches its full open circuit position to bend the pawl and cause rotation of the arc-extinguishing tube 210 a predetermined amount. This will occur as stated when tube 210 moves to its open circuit position, so that on successive circuit opening operations, different surfaces of tube 210 will be presented to the arcs formed on such successive circuit opening operation. No retaining pawl is illustrated in connection with this embodiment of the invention because the friction between arc-extinguishing tube 210 and its guide plate extensions 212 will tend to hold the tube at any adjusted position. However, such a retainer pawl may be provided if desired, such for example, as between bearing sleeve 228 and the adjacent portion of actuating member 226, similar to the arrangement shown in Figs. 7 and 8 between housing 122 and tubular member 136.

Having described preferred embodiments of the invention in accordance with the patent statutes, it is again emphasized that this invention should not be limited to the particular embodiment of circuit interrupter with which it is disclosed, because it will be obvious, particularly to persons skilled in the art, that many modifications and changes may be made therein, and that the in-

vention is adapted for use with other types of circuit interrupters. Accordingly, it is desired that the invention be interpreted as broadly as possible in accordance with the following claims.

I claim as my invention:

5. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for pivotal movement on an axis which extends transversely of said passage and is located at a point spaced from said point of arc establishment in the direction of arc drawing movement, and means responsive to successive circuit interrupting operations to rotate said portion of said material an amount sufficient to expose different parts of said rotatable portion of said material to said point of arc establishment on such succeeding circuit interrupting operations.
10. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least the portions of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
15. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
20. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
25. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
30. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
35. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
40. In a circuit interrupter, means of insulating material defining opposed inner wall portions of a narrow slot arc passage, said material being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material located at opposite sides of said slot in proximity to said point of arc establishment being mounted for movement relative to said point, and means responsive to successive circuit interrupting operations to move said portions of said material an amount sufficient to expose different parts of said movable portions of said material to said point of arc establishment on such succeeding circuit interrupting operations.
45. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
50. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
55. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
60. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
65. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
70. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.
75. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least a portion of said gas evolving material being mounted for movement relative to said point of arc establishment, and ratchet mechanism associated with said contacts and said movable portion of gas evolving material and arranged to move said portion of said material an amount sufficient to expose different parts of said movable portion of said material to said point of arc establishment on such succeeding circuit interrupting operations.

13

nism associated with said contacts and said movable portion of gas evolving material and arranged to move said movable portion of said material in response to movement of said contacts into engagement an amount sufficient to expose successive parts of said movable portion of said material to said point of arc establishment on such succeeding circuit interrupting operations in response to movement.

5. In a circuit interrupter, means of insulating material defining opposed inner wall portions of a narrow slot arc passage, said material of at least one inner wall portion being capable of evolving an arc-extinguishing gas when in proximity to an electric arc in extinguishing the arc, a contact supported adjacent one edge of said slot, a cooperating contact mounted for movement through said slot into and out of engagement with said first-mentioned contact, at least the portion of gas evolving material at one side of said slot adjacent said first-mentioned contact being mounted for movement relative to said first-mentioned contact, and means responsive to movement of said movable contact for moving said movable portion of gas evolving material to thereby expose different parts of said material to successive arcs established by successive circuit opening movements of said movable contact.

6. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, a contact supported adjacent one edge of said slot, a cooperating contact mounted for movement through said slot into and out of engagement with said first-mentioned contact, at least the portion of gas evolving material at one side of said slot adjacent said first-mentioned contact being mounted for movement relative to said first-mentioned contact, and means responsive to movement of said movable contact into engagement with said first-mentioned contact for moving said movable portion of gas evolving material to thereby expose different parts of said material to successive arcs established by successive circuit opening movements of said movable contact.

7. In a circuit interrupter, means of insulating material defining at least inner wall portions of an annular arc passage, said material of at least one inner wall portion being capable of evolving an arc-extinguishing gas when in proximity to an electric arc to extinguish said arc, means for establishing an arc longitudinally in said passage, and means responsive to successive circuit opening operations for causing relative annular movement of the first two mentioned means so that different portions of said gas-evolving material are exposed to successively established arcs.

8. In a circuit interrupter, tubular means at least partially of insulating material for defining the outer surface of an arc passage, means at least partially of insulating material positioned in said tubular means and spaced therefrom at least during each circuit interrupting operation to define the inner wall of said passage, at least a portion of one of said means forming a wall of said arc passage being of an insulating material which is capable of evolving an arc-extinguishing gas, means for establishing an arc longitudinally of said passage, and means for rotating at least said one wall-forming means substantially about its longitudinal axis a predetermined increment

14

in response to successive circuit interrupting operations to thereby present different parts of said gas-evolving material to such successive arcs.

9. In a circuit interrupter, tubular means at least partially of insulating material for defining the outer surface of an arc passage, means at least partially of insulating material positioned in said tubular means and spaced therefrom at least during each circuit interrupting operation to define the inner wall of said passage, at least portions of the walls of said arc passage being of an insulating material which is capable of evolving an arc-extinguishing gas, means for establishing an arc longitudinally of said passage, and means for rotating said wall-forming means substantially about their longitudinal axes a predetermined increment in response to successive circuit interrupting operations to thereby present different parts of said gas-evolving material to such successive arcs.

10. In a circuit interrupter, tubular means at least partially of insulating material for defining the outer surface of an arc passage, means at least partially of insulating material positioned in said tubular means and spaced therefrom at least during each circuit interrupting operation to define the inner wall of said passage, at least portions of the walls of said arc passage being of an insulating material which is capable of evolving an arc-extinguishing gas, means for establishing an arc longitudinally of said passage, and means for rotating said wall-forming means substantially about their longitudinal axes a predetermined increment in response to successive circuit interrupting operations to thereby present different parts of said gas-evolving material to such successive arcs.

11. In a circuit interrupter, tubular means at least partially of insulating material forming an arc passage, separable contacts one of which is movable away from the other substantially longitudinally through said passage to draw out the arc in a circuit interrupting operation, means at least partially of insulating material having a cross sectional area at least slightly less than the cross sectional area of said passage adapted to follow said movable contact through said passage during a circuit interrupting operation to restrict the arc, at least one of said means having at least a portion of its surface exposed to said arc of an insulating material which is capable of evolving an arc-extinguishing gas when in proximity to an electric arc, and means for rotating at least said one means substantially about its longitudinal axis a predetermined increment in response to successive circuit interrupting operations to thereby present different parts of said gas-evolving material to such successive arcs.

12. In a circuit interrupter, tubular means at least partially of insulating material for defining the outer surface of an arc passage, means at least partially of insulating material positioned in said tubular means and spaced therefrom at least during each circuit interrupting operation to define the inner wall of said passage, at least portions of the walls of said arc passage being of an insulating material which is capable of evolving an arc-extinguishing gas, means for establishing an arc longitudinally of said passage, and means for rotating said wall-forming means substantially about their longitudinal axes in response to successive circuit interrupting operations to thereby present different parts of said gas-evolving material to such successive arcs.

13. In a circuit interrupter, tubular means at least partially of insulating material forming an arc passage, separable contacts one of which is movable away from the other substantially longitudinally through said passage to draw out the arc in a circuit interrupting operation, means at least partially of insulating material having a cross sectional area at least slightly less than the cross sectional area of said passage adapted to follow said movable contact through said passage during a circuit interrupting operation to restrict the arc, said means having at least portions of their surfaces exposed to said arc of an insulating material which is capable of evolving an arc-extinguishing gas when in proximity to an electric arc, and means for rotating said means substantially about their longitudinal axes a predetermined increment in response to successive circuit interrupting operations to thereby present different parts of said gas-evolving material to such successive arcs.

14. In a circuit interrupter, tubular means at least partially of insulating material forming an arc passage, movable means at least partially of insulating material adapted to move into said passage during a circuit interrupting operation to restrict the arc in said space, said movable means having at least a portion of its surface exposed to said arc of an insulating material which is capable of evolving an arc-extinguishing gas when in proximity to an electric arc, and means for rotating said movable means substantially about its longitudinal axis a predetermined increment in response to successive circuit interrupting operations to thereby present different parts of said gas-evolving material to such successive arcs.

15. In a circuit interrupter, means of insulating material defining opposed inner wall portions of a narrow slot arc passage, said material of at least one inner wall portion being capable of evolving an arc-extinguishing gas when in proximity to an electric arc to aid in extinguishing the arc, separable contacts adapted when separated to establish an arc at one point in said passage and draw out the arc through said passage, at least the portions of said gas-evolving material located at opposite sides of said slot in proximity to said point of arc establishment being mounted for movement relative to said point, and means responsive to successive circuit interrupting operations to move said portions of said material in opposite directions an amount sufficient to expose different parts of said movable portions of said material to said point of arc establishment on such succeeding circuit interrupting operations.

16. In a circuit interrupter, spaced walls defining an arc passage therebetween at least when an arc is struck in said passage, said space between said walls being relatively small so that said walls will be in close proximity to the arc, at least inner surfaces of said walls being of an insulating material and at least one inner wall of said passage comprising at least in part insulating means which is capable of evolving an arc-extinguishing gas when in proximity to an electric arc, means for establishing an arc in said passage, and means responsive to an operation of said interrupter for automatically relatively moving at least a part of said gas-evolving material and said arc-establishing means in a direction extending generally in the direction of the inner surface of said one inner wall without disturbing

the spacing of said walls, so that different portions of said gas-evolving material will be brought into proximity with successive arcs.

17. In a circuit interrupter, spaced walls defining an arc passage therebetween at least when an arc is struck in said passage, said space between said walls being relatively small so that said walls will be in close proximity to the arc, at least inner surfaces of said walls being of an insulating material and at least one inner wall of said passage comprising at least in part insulating means which is capable of evolving an arc-extinguishing gas when in proximity to an electric arc, means for establishing an arc in

10 said passage, at least a portion of one of said means being mounted for movement relative to the other of said means in the direction of the inner surface of said one inner wall, and means for automatically moving said one means between successive circuit interrupting operations without disturbing the spacing of said walls, so that different portions of said gas-evolving material will be brought into proximity with successive arcs.

25 18. In a circuit interrupter, spaced walls defining an arc passage therebetween at least when an arc is struck in said passage, said space between said walls being relatively small so that said walls will be in close proximity to the arc,

30 at least inner surfaces of said walls being of an insulating material and at least one inner wall of said passage comprising at least in part insulating means which is capable of evolving an arc-extinguishing gas when in proximity to an electric

35 arc, means for establishing an arc in said passage along a predetermined path, at least the portion of said gas-evolving material located in proximity to the initially formed portion of said arc being mounted for movement at an angle to said predetermined path, and means responsive to successive circuit interrupting operations to move

40 said portion of said gas-evolving means an amount sufficient to expose a different portion of said gas-evolving material to said initial part of the 45 arc on a succeeding circuit interrupting operation without disturbing the spaced apart relation of said wall portions.

19. In a circuit interrupter, spaced walls defining an arc passage therebetween at least when an arc is struck in said passage, said space between said walls being relatively small so that said walls will be in close proximity to the arc, at least inner surfaces of said walls being of an insulating material and at least one inner wall of

55 said passage comprising at least in part insulating means which is capable of evolving an arc-extinguishing gas when in proximity to an electric arc, separable contacts adapted when separated to establish an arc at one point in said passage

60 and draw out said arc through said passage, and means actuated by at least one of said contacts for relatively moving at least a part of said gas-evolving material and said contacts in a direction extending generally in the direction of the inner

65 surface of said one inner wall without disturbing the spacing of said walls, so that different portions of said gas-evolving material will be brought into proximity with successive arcs.

20. In a circuit interrupter, tubular means at least partially of insulating material for defining the outer surface of an arc passage, means at least partially of insulating material positioned in said tubular means and spaced therefrom at least during each circuit interrupting operation to define the inner wall of said passage, at least

portions of the walls of said arc passage being of an insulating material which is capable of evolving an arc-extinguishing gas, means for establishing an arc longitudinally of said passage, and means for rotating said wall-forming means substantially about their longitudinal axes predetermined different increments, respectively, in response to successive circuit interrupting operations to thereby present different parts of said gas-evolving material to such successive arcs.

21. A switch, comprising, a support, a disconnect contact, arc passage means and a first interrupting contact all mounted in proximity on said support with said first interrupting contact permanently located in said passage means and 15 electrically connected with said disconnect contact, a switch blade mounted for movement on said support into and out of engagement with said disconnect contact, a second interrupting contact mounted on said blade for movement thereby to and away from said passage and through said passage into and out of engagement with said first interrupting contact, spaced walls defining said arc passage therebetween at least when an arc is struck in said passage, the space 20 between said walls being relatively small so that said walls will be in close proximity to arcs struck 25
